BAKING PAN FOR CORN STICKS OR
THE LIKE

Harry Goodman, Britton, and Ralph M. Wolfe,
Oklahoma City, Okla., assignors to Little Giant
Vaporizer Co., Inc., Oklahoma City, Okla.

Application November 17, 1947, Serial No. 142,567

Term of patent 3½ years

(Cl. D44—1)

To all whom it may concern:

Be it known that we, Harry Goodman and Ralph M. Wolfe, both citizens of the United States, residing, respectively, at Britton and Oklahoma City, in the county of Oklahoma and State of Oklahoma, have invented a new, original, and ornamental Design for a Baking Pan for Corn Sticks or the like, of which the following is a specification, reference being had to the accompanying drawings, forming part thereof.

Fig. 1 is a perspective view of a baking pan for corn sticks or the like, showing our new design; and

Fig. 2 is a vertical sectional view taken transversely through the pan of Fig. 1, at its center.

We claim:

The ornamental design for a baking pan for corn sticks or the like, as shown.

HARRY GOODMAN.
RALPH M. WOLFE.
